UNITED STATES PATENT OFFICE.

ALBERT OLIVER, OF MAMARONECK, NEW YORK.

PLASTER WALL.

Application filed July 18, 1923. Serial No. 652,261.

To all whom it may concern:

Be it known that I, ALBERT OLIVER, a citizen of the United States, and a resident of Mamaroneck, in the county of West Chester and State of New York, have invented certain new and useful Improvements in Plaster Walls, of which the following is a full, clear, and exact description.

10 The principal object of the invention is to provide for a novel form of plaster wall construction which will be of great strength and durability, and capable of being set up or formed in position without the usual and costly framing structure to support the same, such as is necessary to meet the modern demand of reducing the amount of structural materials requiring the employment of skilled labor for its installation and to 20 otherwise effect a lowering of the cost of building designed for human habitation.

Another object of the invention is to provide for a metal ground, lathing or reinforcement for plaster walls or partitions and the like, and one of a construction and arrangement of parts whereby to be of great strength and rigidity and capable of sustaining the weight of plastic coatings applied to one or both sides without the co-operation therewith of the usual wall or partition studding, which are to be either wholly eliminated, or otherwise greatly reduced in number, when the invention is put into practice.

35 A further object of the invention is to provide for a ground or reinforcement of the character mentioned, and one of a novel laminated construction consisting of a plurality of layers or sheets of wire mesh separated by layers or sheets of paper or other suitable fabric, whereby the plastic material or coatings will be prevented from passing from one side to the other of the ground or reinforcement during its application to one or both sides thereof, the said paper or fabric to be suitably water-proofed, when the ground or reinforcement is to be used in the construction of outside walls.

Another object of the invention is to provide for a ground or reinforcement of the type set forth, and one wherein the several layers or sheets of wire mesh and paper or fabric aforesaid are to be secured together in a novel and efficient manner to form a substantially unitary structure capable of being readily manufactured and sold in sections of either special or standard dimensions.

A still further object of the invention is to provide for a ground or reinforcement of the class mentioned, and one for use in the construction of any and all thicknesses of walls, both inner and outer, of plastic materials, and which will be practically sound-proof, especially when used in relatively thin partition walls such as are ordinarily employed in apartment houses and office buildings.

With the foregoing and other equally important objects in view, the invention resides in the certain novel and useful construction as will be hereinafter more fully described, set forth in the appended claims, and illustrated in the accompanying drawings, in which:

70 Figure 1 is a fragmentary perspective view of the interior of a building, and showing a partition wall as constructed and arranged in accordance with the present invention,

75 Figure 2 is a horizontal section through the partition wall per se, and showing the ground or reinforcement as it appears when coated on its opposite sides with plastic materials,

80 Figure 3 is an elevation of one side of a preferred form of the metal lathing, ground or reinforcement,

85 Figure 4 is a fragmentary elevation of the opposite side thereof,

90 Figure 5 is a side elevation of the sound deadening lamination or sheet, with a portion thereof broken away to show the fiber or excelsior filling of the interior of the same,

95 Figure 6 is a similar view of the sound

deadening pad or sheet, with the addition thereto of an outer sheet or layer of a water-proofed material.

Figure 7 is a fragmentary elevation of a slightly modified form of the plaster ground, and showing the alternate arrangement of the several laminations or sheets of wire mesh and layers of paper thereof, and,

Figure 8 is a horizontal section thereof through, but with plaster coatings applied in part to the opposite sides of the same.

Referring to the drawings, wherein similar characters of reference designate corresponding parts throughout the several views thereof, and with particular reference to Figure 1 through 5, the preferred embodiment of the wall base or reinforcement comprises a laminated body of sheet form made up of a plurality of superposed sheets of open mesh metallic fabric or material 10, 11 and 12, and a paper loaded quilt or the like 14 interposed between the wire mesh sheets 11 and 12.

The lamination or sheet 10 is preferably of the well known "Clinton" type of wire mesh, wherein the meshes thereof are rectangular or oblong in configuration, and the transversely extending wires 10' thereof are spot welded to the parallel longitudinal or vertical wires 10" at their points of crossing therewith. The lamination or sheet 10 may be of a heavier gauge of wire and have larger mesh openings than the laminations or sheets 11 and 12, if desired, or the same 35 may be of equal gauge or grade and size of mesh as the latter, but, in any case, the laminations or sheets 11 and 12 will be of a less costly wire fabric than the lamination or sheet 10, and preferably of the regular 40 "chicken" or "rabbit" type of wire mesh of the woven forms thereof.

The paper lamination or sheet 14 is preferably formed of two sheets of ordinary building paper or the like, padded or quilted 45 with a filling of a fibrous material, such as paper excelsior, between the same, the two sheets of paper being designated 14^a and 14^b, and the filling 14^c, wherever they appear in the drawings. This padded sheet 14 acts to 50 deaden the sound at either side of a wall having the ground or reinforcement embedded within the same, and, when incorporated in the reinforcement in the manner indicated for the same, admits of the construction of relatively thin walls, such as 55 the partition walls of apartment and office buildings, without fear of sounds and noises being transmitted through the wall from one side to the other thereof. This 60 paper sheet 14 is preferably interposed between the wire mesh sheets 11 and 12 which are of a sufficient strength to prevent the paper from buckling or breaking during the application of the plaster coatings to one or 65 both sides of the reinforcement.

In the construction of outside walls or buildings or the like, it is sometimes desirable to protect the padded sheet 14 from moisture at the outer side thereof, and to such end, a sheet of a water-proofed paper 70 13 will be disposed at the outer side of the sheet 14 and between the wire mesh sheets 11 and 12. As shown in Figure 6, the padded sheet 14 will be first laid on the water-proofed sheet 13, and then both sheets 75 will be interposed between the said sheets of wire mesh 11 and 12. However, the water-proofed sheet 13 may, if desired, be interposed alone between the wire mesh sheets 10 and 11, with the padded sheet 14 between 80 the wire mesh sheets 11 and 12, but, in any case, the sheet 13 will be disposed at the outer side of the sheet 14 to fully cover and protect the opposed side thereof.

As shown in Figures 7 and 8, a sheet of 85 building paper or the like is interposed between the sheets of wire mesh 10, 11 and 12, the paper sheet 13 between the wire mesh sheets 10 and 11, and the paper sheet 14 between the wire mesh sheets 11 and 12, and 90 in this case the wire mesh sheet 10 will still be made of the "Clinton" type of wire mesh, while the sheets 11 and 12 are of any standard but less costly type of wire mesh, substantially as shown. In this instance of the 95 invention, one or both of the paper sheets 13 and 14 may be water-proofed, especially when the ground or reinforcement is to be used in the construction of outside walls.

To secure the several laminations or 100 sheets of wire mesh 10, 11 and 12 and of paper 13 and 14, together and into final unitary form, and after their assembly into the alternate arrangement as hereinbefore explained, certain of the longitudinal members or wires 10", of the lamination or sheets 10 are provided with a plurality of equidistantly spaced loop portions 15 offset to one side of the same, which are to be pushed through the paper laminations 13 and 14 and the aligned meshes of the wire mesh laminations 11 and 12, and until the sheet 10 closely abuts the adjacent sheet or lamination of wire mesh 11, on the one hand, or the opposed face of the paper sheet or lamination 13, on the other hand, when the free ends of the loop portions 15 will project outwardly of the sheet or lamination 12. These spaced loop portions 15 are arranged in vertical rows, so that separate straight wires or rods 16 may be threaded through the same to bind or tie the several sheets or laminations tightly together. The extremities 16' of these tie wires or rods 16, are preferably bent over the outer edges of the laminations or sheets and clinched thereover to form a continuous and permanent structure. The intervals between the loop portions 15, both vertically and horizontally, are a matter of de- 130

sign and vary in accordance therewith. The tie wires or rods 16, by being extended vertically, assist in sustaining any crushing weight placed on the walls or partitions reinforced with the grounds, and the gauge or weight of the same will be practically equal to that of the vertical elements 10' of the sheet or lamination 10 for such purpose. In all arrangements, sufficient strength is imparted to prevent the separation between the metal laminations or sheets further than the flexibility of the fabric or paper laminations or sheets 13 and 14 will accommodate, the object being at all times to avoid breaking the latter by the pressure incident to the applying of plaster to the ground or reinforcement.

Any suitable method of applying the reinforcement or ground to the standing structure may be employed, and it is particularly desirable that the strength and rigidity of the same be such that few, if any, of the usual wall or partition studding be made use of, so as to reduce the cost of building construction generally, but, in the case of the presence of wooden studding, the reinforcement or ground sections or units are to be fastened thereto by means of staples or the like and at the opposite sides thereof. In this case, plaster will only be applied to the outer sides of the reinforcements at the opposite sides of the partition studding, after the manner usually employed in lathed and plastered walls. In the use of metal uprights or studding, the grounds or reinforcements may be applied thereto by any of the usual forms of clips, bolts, rivets, or tying wires, as may be most convenient or desired. Where no studding is employed, the reinforcements or grounds will be fastened or anchored at their upper and lower side edges to the ceiling and floor structures, when plaster can be readily applied to the opposite sides of the same, which is particularly desirable in modern building and house construction. By making use of the reinforcement having the layer or lamination 14, of padded paper or other material, relatively thin partition walls may be constructed without the noise or sound at one side of a wall being transmitted to the other side thereof, by mounting the reinforcements without studding supports and applying the plaster directly to the opposite sides of the same. This is also true in the manufacture of outside walls, but, of course, the outer plaster coating should be laid on to a greater thickness than would otherwise be necessary. In cement or stucco building construction, the cement or stucco grouting will be applied directly to the outer side of the continuous surface sheet 13 and over the metallic lamination 10 to embed the latter therein, the plastic material being applied in any suit-

able or known manner, as by being squirted against the laminations or sheets 10 and 13 with a "Hiscox" gun, in the use of which layer after layer of the grouting is squirted or sprayed one upon the other until the desired thickness of plaster is reached. The interior plaster finish of the wall or walls is afterwards spread or otherwise applied over the laminations or sheets 12 and 14 in the usual manner.

It will be readily obvious that these grounds or reinforcements may be manufactured in assembled form for shipment from the factory to the point of use, or the separate laminations or sheets may be assembled directly at the point of use, but, it has been found that the same are much more satisfactory for handling and are more accurately assembled at the factory than when separately delivered for assembling on the job.

From the foregoing, it will be well understood that, while preferred embodiments of the reinforcement or ground have been described and illustrated herein in specific terms and details of construction and arrangement, various changes in and modifications of the same may be resorted to without departing from the spirit of the invention, or the scope of the claims appended hereto.

Having thus fully described the invention, what is claimed, is:

1. A plastic wall reinforcement comprising a plurality of sheets of an open mesh material, one of the outer of said sheets being of a heavier grade than the others thereof, a sound deadening sheet of continuous surface material interposed between the sheets of open mesh material of the lighter grade, securing loops carried by the sheet of heavy grade of open mesh material and passing through the other of the sheets of open mesh material and the said sheet of sound deadening material, and straight members adapted to be engaged through aligned sets of said securing loops at the opposite side of the reinforcement for retaining the sheets in assembled condition.

2. A plastic wall reinforcement comprising a plurality of sheets of open mesh material, a sheet of continuous surface material alternately interposed between said sheets of open mesh material, means carried by one of the outer of the said sheets of open mesh material and passing through the other of such sheets and the said sheets of continuous surface material, and means disposed at the outer side of the opposite outer sheet of open mesh material and cooperative with said first mentioned means for securing all of the said sheets together.

3. A plastic ground comprising a plurality of sheets of an open mesh material disposed in superposed relation, one of the

outer of said sheets being of a heavier construction than the others thereof, said heavier sheet of open mesh material embodying longitudinally and transversely crossed members forming meshes substantially rectangular in configuration, looped portions formed at one side of the said longitudinal members of said heavier sheet of open mesh

material and adapted to be passed through the other of such sheets and the said sheets of continuous surface material, and means adapted to be engaged through said looped portions at the inner side of the ground for securing the said several sheets together.

ALBERT OLIVER.
